CLAIM

The ornamental design for a combined bird perch and beak sharpener, as shown and described.

DESCRIPTION

FIG. 1 is a perspective view of a combined bird perch and beak sharpener showing my new design;

FIG. 2 is a top plan view thereof;

FIG. 3 is a front elevational view thereof, the rear view being a mirror image;

FIG. 4 is a right side elevational view, the left side elevational view being a mirror image;

FIG. 5 is a bottom plan view thereof; and,

FIG. 6 is a perspective view of a second embodiment of FIG. 1, the opposite side and end are identical to that shown.

The broken lines in FIGS. 1 and 6 are for purposes of illustration only and form no part of the claimed design.

FIG. 1.

FIG. 2.

FIG. 3.

FIG. 4.

FIG. 5.

FIG. 6.
